W. M. Knapp

UNITED STATES PATENT OFFICE.

VOLNEY A. SEARLES, OF JACKSON, MICHIGAN, ASSIGNOR TO STEWART-WARNER SPEEDOMETER CORPORATION, OF CHICAGO, ILLINOIS, A CORPORATION OF VIRGINIA.

LIQUID-FEEDING DEVICE.

Application filed October 19, 1923. Serial No. 669,478.

This invention relates to certain improvements in liquid feeding devices for use particularly in supplying liquid fuel to internal combustion engines of automobiles and the like, in connection with which it is very often desirable to have the primary fuel tank carried on the vehicle at a level below the carburetor.

Such tank structures usually embody an upper chamber and a lower chamber with valved means of communication between them for effecting intermittent discharge from the upper chamber to the lower chamber when atmospheric pressure exists in the upper chamber.

The primary object of this invention is to provide a novel means for controlling the siphonic connections between the upper and lower chambers combined with means for renewing the siphon to automatically start the operation of the device, in effecting the intermittent discharge of liquid from the upper to the lower chamber.

Other objects and advantages relate to the details of construction of the device, all as will more fully appear from the following description, taken in connection with the accompanying drawings, in which:

Figure 1 is a vertical sectional view through the tank construction.

Figure 2 is an enlarged sectional view of the float and its appurtenances which control the siphonic connection.

Figure 3 is a view of the method of pivoting the float which actuates the float valve to effect renewing of the siphon.

As illustrated, the liquid feeding device comprises a tank —1—, divided by a partition —2— into an upper chamber —3— and a lower chamber —4—. The upper chamber is provided with the usual liquid connection —39—, suction connection —40— and atmospheric connection —41—. The suction connection is controlled by valve —42— mounted upon a float stem —5— which moves in conjunction with the float —6— disposed in the chamber —3—, while the atmospheric vent —41— is controlled by a valve —7— actuated by a lever —8— adapted to be moved by spring —9— which has its outer end connected to the lever —8— and its inner end connected to the float stem —5—, so that as the float stem moves the spring —9— to opposite sides of the pivot —10— of the lever

—8— the valve —7— will be snapped to open or closed position, in accordance with the position of the float. An additional spring —11— is provided connected to the float and to an extending projection —12— for balancing the spring —9—.

The construction and operation of these parts of the device are the same as those shown in Letters Patent No. 1,255,347, issued to William Sparks under date of February 5, 1918. The connection between the chamber —4— from which liquid is adapted to be discharged by gravity through a pipe —13— to any suitable consuming device as the carburetor, is effected by means of the siphon tube

—14— which preferably extends to substantially the lower part of the chamber —4—, and penetrates the partition wall —2—. The other end of this siphon terminates in chamber —3— and is provided with a valve chamber —15— which contains a float valve —16—

which may be of cork, or any other suitable material adapted to be buoyed by the liquid in chamber —3—, so as to automatically open the passage —17— when atmospheric condition exists in chamber —3—. To prevent the float from closing the siphon when it is moved upwardly by the buoyancy of the liquid the leg —18— preferably penetrates the valve casing —15— and extends some distance into the valve casing, and is provided with a series of recesses —19— in its lower end forming means of communication between the siphon leg —18— and the valve chamber —15—.

A normal level of liquid is maintained by this structure in chamber —3— so as to keep the float —21— in a position shown in Figure 1 so that the projection —22— does not interfere with the closing of the float valve —16— by gravity. This float —21— is preferably mounted upon a stem pivoted in journals —23— carried by the lower end of the valve casing —15— and has a projection —22— adapted to lie in the position shown in Figure 1, or when the level of liquid is such that the float —21— is not maintained in the position shown in Figure 1, it may drop to any position, as limited by contact of projection —22— with the wall of the opening —17— as shown in Figure 2.

It will be seen that if the level of liquid in the chamber —3— drops below the normal level which would maintain float —21— in

the position shown in Figure 1, the lowering of float —21— will elevate the projection —22— into the port governed by the float valve —16— maintaining the same in open position, so that the suction produced in the upper chamber will elevate the liquid from the chamber —4— through the siphon tube into chamber —3— until sufficient liquid has been raised in the chamber —3— so as to move the float —21— to the position shown in Figure 1, or to such a position that the projection —22— does not lie in the path of the closing movement of the float valve —16—. In other words, if the normal level of liquid is not maintained in chamber —3—, the siphon will be renewed by elevation of liquid through the siphon tube into the chamber —3—, and from that point on all liquid fuel will be drawn from the rear tank until the motor stops. When the motor starts again the siphon is renewed in the same manner.

It will be understood that the connection of the chamber —3— with the suction line and the atmospheric vent depends upon the position of the float —6—, and, therefore, upon the amount of liquid in chamber —3— the operation of this construction being well known in the art. The valve —16— is held in closed position by the suction during the existence of vacuum in the chamber —3—, and upon the production of atmospheric pressure therein, is raised from its seat by the buoyancy of the liquid.

A normal level of liquid is maintained in the lower chamber —4— above the discharge end of the siphon tube —14— so that the renewal of the siphon above described can be effected by elevation of liquid in chamber —4— into chamber —3— at the starting of the operation of the device, should that be necessary.

Although I have shown and described a particular construction as illustrative of a perhaps preferred embodiment of my invention, I do not desire to limit myself to the details of construction or operation of the device, as various changes, modifications and substitutions may be made without departing from the invention as set forth in the appended claims.

I claim:—

1. In a device of the class described, an upper chamber and a lower chamber, means for alternating vacuum and atmospheric pressure in the upper chamber, a siphon tube connecting said chambers and having one leg terminating in the upper chamber and its other leg terminating in the lower chamber, a float valve controlling communication of said siphon with the upper chamber, and means for holding said float valve open when the level of liquid in the upper chamber is below a predetermined point. 55

2. In a device of the class described, an upper chamber and a lower chamber, means for maintaining atmospheric pressure in the lower chamber, means for alternating vacuum and atmospheric pressure in the upper chamber, a siphon tube having one leg terminating in the upper chamber and its other leg terminating in the lower chamber, a valve casing associated with the end of said leg terminating in the upper chamber, a float in said chamber adapted to close communication between the upper chamber and said siphon tube, and means for holding said float in a position to permit communication between the upper chamber and the siphon tube when the liquid in the upper chamber is below a predetermined level. 70

3. In a device of the class described, an upper chamber and a lower chamber, means for alternating vacuum and atmospheric pressure in the upper chamber and a siphon tube connecting said chambers and having one leg terminating in the upper chamber and the other leg terminating in the lower chamber, a buoyancy-actuated valve controlling communication of said siphon with the upper chamber and means for holding said valve open when the level of liquid in the upper chamber is below a predetermined point, said means comprising a lever arm fulcrumed between its ends with a float at one end and with the other end disposed to engage said valve through the port which it governs. 85 90

In witness whereof, I have hereunto set my hand this 2nd day of October, 1923.

VOLNEY A. SEARLES.
